[57] CLAIM

The ornamental design for a training urinal, as shown and described.

DESCRIPTION

FIG. 1 is a frontal perspective view of a training urinal, showing my new design therefor;

FIG. 2 is a bottom plan view;

FIG. 3 is a top plan view;

FIG. 4 is a front elevation view;

FIG. 5 is a rear elevation view; and

FIG. 6 is a right-side elevational view, it being understood that the left-side is a mirror image thereof.

FIG. 1

FIG. 2

FIG. 3

FIG. 4

FIG. 5

FIG. 6

UNITED STATES PATENT AND TRADEMARK OFFICE
CERTIFICATE OF CORRECTION

PATENT NO. : Des. 318,325

DATED : July 16, 1991

INVENTOR(S) : James C. McKinney

It is certified that error appears in the above-identified patent and that said Letters Patent is hereby corrected as shown below:

On the title page: change "[76] Inventor: James C. McKinney, 3315 W. Los Reales, Tuscon, Ariz. 85746" to --[76] Inventor: James C. McKinney, 557 Quandt Ranch Road, San Jacinto, California 92383--.

Signed and Sealed this
Twenty-seventh Day of October, 1992

Attest:

DOUGLAS B. COMER

Attesting Officer

Acting Commissioner of Patents and Trademarks
